UNITED STATES PATENT OFFICE

JAMES J. SERIGHT, OF LINCOLN, NEBRASKA

DESIGN FOR AN EMBLEM OR LIKE ARTICLE

Application filed June 12, 1931. Serial No. 40,178. Term of patent 3½ years.

To all whom it may concern:

Be it known that I, JAMES J. SERIGHT, a citizen of the United States residing at Lincoln, in the county of Lancaster and State of Nebraska, have invented a new, original, and ornamental Design for an Emblem or like Article, of which the following is a specification, reference being had to the accompanying drawing, forming part thereof.

Figure 1 is a front elevational view of an emblem or like article showing my new design; and

Figure 2 is an edge elevational view thereof.

I claim:

The ornamental design for an emblem or like article, as shown.

In testimony whereof I affix my signature.

JAMES J. SERIGHT.
